UNITED STATES PATENT OFFICE

164,164

BOTTLE STOPPER

Carl Gossman, Glenwood, Ill.

Application July 23, 1949, Serial No. 4,097

Term of patent 7 years

(Cl. D58—10)

To all whom it may concern:

Be it known that I, Carl Gossman, a citizen of the United States, residing at Glenwood, Cook County, Illinois, have invented a new, original, and ornamental Design for a Bottle Stopper, of which the following is a specification, reference being had to the accompanying drawings, forming a part thereof.

Fig. 1 is an elevational view of a bottle stopper, showing my new design;

Fig. 2 is a top view of the bottle stopper shown in Fig. 1;

Fig. 3 is a vertical section taken through the bottle stopper substantially along the line 3—3 in Fig. 2, and showing the locking ring, which surrounds the stopper, in lowered locking position thereon.

I claim:

The ornamental design for a bottle stopper, as shown.

CARL GOSSMAN,
